CLAIM

The ornamental design for a media player device docking station, as shown and described.

DESCRIPTION

FIG. 1 is a top plan view of a media player device docking station.

FIG. 2 is a bottom plan view thereof.

FIG. 3 is a front elevation view thereof.

FIG. 4 is a rear elevation view thereof; and,
FIG. 5 is a perspective view thereof.

The dash-dash broken lines show features of the media player device docking station that form no part of the claimed design. The dot-dash broken lines show boundaries of the claim and form no part of the claimed design.

1 Claim, 4 Drawing Sheets
